UNITED STATES PATENT OFFICE.

WILLIAM McCLOVE, OF SCRANTON, PENNSYLVANIA, ASSIGNOR TO McCLOVE-BROOKS COMPANY, OF SCRANTON, PENNSYLVANIA, A CORPORATION OF PENNSYLVANIA.

FUEL-FEEDING DEVICE.

1,239,612.

Specification of Letters Patent. Patented Sept. 11, 1917.

Application filed June 27, 1913. Serial No. 776,123.

To all whom it may concern:

Be it known that I, WILLIAM McCLOVE, a citizen of the United States, and resident of Scranton, in the county of Lackawanna and State of Pennsylvania, have invented certain new and useful Improvements in Fuel-Feeding Devices; and I do hereby declare the following to be a full, clear, and exact description of the same, reference being had to the accompanying drawings, forming part of this specification, and to the figures and letters of reference marked thereon.

Furnaces to which the present invention is particularly applicable are designed for heating boilers, etc., with bituminous coal, but are also especially adapted for the consumption of low grade or cheap coal fuel, such as bituminous slack, etc., or with mixtures of the smaller sizes of anthracite with bituminous slack, etc., which are not easily consumed with economy in furnaces of ordinary construction. The invention has for its objects to provide a furnace in which the fuel may be automatically fed to the grate or firebox in such manner as to insure the complete combustion of the combustible elements therein without the production of objectionable smoke in the waste gases. To these ends it contemplates a construction in which the fuel will be initially supplied to a hopper or hoppers located at the upper end of an inclined grate, which grate extends downwardly and inwardly into the combustion chamber, preferably with its fuel supporting surfaces in substantially a single plane. The fuel is advanced down over the inclined grate by a pusher or pushers operating below the mouth of the hopper in a plane which is parallel with and immediately above the grate, whereby the fuel will be advanced in a sheet or body of substantially uniform depth or thickness. In connection with this arrangement of the parts, provision is made, whereby a rousing-bar may be introduced in the plane of the pusher or in the plane of the lower portion or stratum of fuel resting on the grate for slightly lifting or distributing the lower portion of the fuel to facilitate the passage of air into and through the same, without,

however, breaking up the fuel to such an extent that a rush of air will result and cause the production of smoke. In this connection it may be here noted that it is the generally accepted theory that the chief cause of smoke is due to the fact that hydrogen has a greater affinity for oxygen than has the carbon. The initial heating of the fuel results in the distillation of a large quantity of hydrogen which appropriates the major portion of the incoming oxygen, leaving an insufficient supply for the carbon. The intense heat of the burning hydrogen sets free quantities of carbon in an exceedingly comminuted condition and this carbon is carried off without being chemically combined with oxygen. The waste products pass into the discharge flues and are cooled down to a point at which water vapor results from the hydrogen combination, and this water vapor becomes thoroughly impregnated with the carbon particles which at that temperature assume their natural black color. A very small quantity of carbon is sufficient to densely color a very large quantity of water vapor and the result is the emission of quantities of black smoke. From this it is apparent that to prevent the production of smoke, the constant breaking up of the fuel should be avoided as much as possible; fresh fuel should be introduced or fed to the furnace with as little disturbance as possible and moved along *en masse* at a substantially uniform rate; and at the same time a sufficient supply of preheated air should be introduced at such point or points as is necessary to supply oxygen for combining with the carbon elements set free by the distillation and combustion process.

In addition to the mechanism heretofore referred to as a part of the structure of the furnace of the present invention, the invention contemplates a novel arrangement for supplying preheated air above the fuel in regulated quantities to accord with the requirements existing at any particular moment, for under the conditions stated the quantity of oxygen required varies somewhat, particularly at the times when the lower stratum of the fuel is being disturbed.

and the body of fuel lifted slightly by the rousing-bar to augment the admission of air through the grate. The structure employed also embodies means whereby the 5 fuel feeding devices may be adjusted for any desired rate of feed or instantly disconnected to arrest the feed and for permitting of the quick introduction of a hoe or other implement for breaking up and dis- 10 charging the whole body of fuel in an emergency, without permitting additional fuel to be fed down from the hopper.

The invention consists in the combinations and arrangements of parts and in the 15 detail construction of the elements which will be hereinafter described and pointed out particularly in the appended claims.

Referring to the accompanying drawings,—

20 Figure 1 is a section in a vertical plane from front to rear, of a furnace embodying the present improvements, certain of the well understood parts being indicated more or less diagrammatically, or shown in outline.

Fig. 2 is a front elevation of the structure shown in Fig. 1, and designed as the furnace for one boiler of a battery of boilers;

30 Fig. 3 is a plan view of one of the fuel pushers with its inclosing chamber in section;

Fig. 4 is a detail of a pusher gate operating tool or handle.

Fig. 5 is a front and Fig. 6 an end elevation of one of the furnace shafts showing the operating connections for the power shaft and pusher together with the means for disconnecting the parts when it is desired to arrest the movement of the pusher 40 and for adjusting the throw of the pusher to regulate the quantity of fuel fed to the furnace.

Figs. 7 and 8 are, respectively, a side and edge view of the pusher arm.

45 Figs. 9 and 10 are similar views of the power transmitting arm.

Fig. 11 is a bottom edge view of the power transmitting arm.

50 Figs. 12, 13 and 14 are details of the ends of the furnace shaft and washer for retaining the shaft in place and the operating arms thereon.

Figs. 15 and 16 are plan and side views, respectively, of the connecting rod between 55 the power and furnace shafts.

Fig. 17 is a section on the line A—A of Fig. 16; and

Fig. 18 is a section on the line B—B of Fig. 16, omitting the connecting rod.

60 Like letters of reference in the several figures indicate the same parts.

The furnace adopted for illustrating the present invention is of the projecting furnace type, that is to say, the main combus-

tion chamber is located in front of a wall C, 65 which wall is in substantially the vertical plane of the front of the boiler shown diagrammatically in Fig. 1. The top of the combustion chamber or fire box is formed by an arch D having small openings d therethrough for the entry of preheated air which air is admitted through a preheating chamber D' and distributed to the openings d through suitable passages or channels in 70 or above the arch D.

The grate E occupies an inclined position 75 below the arch D, and while the particular construction of the fuel supporting surface is immaterial, in so far as the present invention is concerned, it is of such character that the fuel will be supported on a surface which is substantially in a single plane inclined at an angle slightly less than the angle of rest of the fuel, fed down over it from the upper end. Formed as a continuation of the upper end of the grate and with its surface in substantially the same plane as the fuel supporting surface of the grate, is a dead plate F, upon which there is mounted a reciprocatory pusher G, two of said pushers being preferably employed for the furnace of each boiler, although in a narrow furnace a single pusher will be sufficient. The pushers are housed in and operate through the lower edges of chambers having top plates H, Fig. 1, and side and front walls H', Fig. 3. They advance fuel which is deposited on the dead plate in front of them from a hopper or hoppers located above, and, as shown in Figs. 1, 2 and 3, formed by end and partition walls I, I', respectively, an inclined front I², and a vertical furnace wall I³. The latter forms the front of the air preheating chamber D' and extends down in rear of the hoppers with passages d' therethrough for the admission of preheated air to the fuel which is advanced by the pushers into the distilling and combustion areas of the grate.

In order that the plates I² may be properly protected from the heat of the combustion chamber, a row of relatively large firebrick D² is located on the inner side of and preferably supported by said plates at the front end of the arch D, as will be readily understood from an inspection of Fig. 1.

The inclined wall I² of the hopper terminates at a point some distance above the top H of the pusher chambers, leaving a relatively large opening through which a hoe or similar implement may be introduced for the purpose of pushing the fuel down the inclined grate and onto a dumping section at the bottom thereof, should an emergency require the drawing of the fires or the complete emptying of the fuel into the ash pit. Under such circumstances, it is, of course, desirable that no additional fuel should be

permitted to flow into the combustion chamber, and for this purpose a curved gate K is pivotally mounted at the lower edge of the inclined wall I² in position to swing down 5 and form a continuation of the wall leading to the forward edge of the pusher chambers, as shown in Fig. 1, but adapted to be swung up to the position shown in dotted lines, when a hoe or other implement is to be introduced 10 for the purpose stated. The swinging gate will carry up with it any fuel lying upon it, and will effectually close the hopper against the escape of additional fuel during the operation of drawing the fire. The opening 15 below the lower edge of the plate I² may also be utilized for the introduction of implements for distributing the fuel on the grate should the same for any cause become banked or unevenly distributed, although 20 this is a condition which is not likely to occur with the present apparatus.

Each pusher is directly operated by two links or connecting rods L which pass out of the pusher chamber through openings 25 best seen in Fig. 3 at the ends of the pusher. At their outer ends the rods or links are pivotally connected with pusher arms L' shown in detail in Figs. 7 and 8, and in assembled relation in Figs. 5 and 6. The pusher arms 30 L' for each pusher are keyed on a furnace shaft M journaled in brackets on the extension front plate N of the furnace. Journaled on one end of each furnace shaft M is a bell crank operating member, one arm O of 35 which is adapted to be connected by a link P to be presently described, with an eccentric strap, surrounding an eccentric on a power shaft Q journaled in suitable brackets on the upper portion of the furnace and rotated continuously from any suitable source 40 of power. The other arm O' of the bell crank operating member is provided with a transverse aperture adapted to register with a similar aperture in the pusher arm L' and 45 to be connected therewith by a headed pin or bolt O² which serves as a ready means whereby the parts may be instantly disconnected should the necessity arise for quickly arresting the feed movements of the pusher. 50 The link P before referred to is at its lower end provided with a slot or elongated opening p in which the crank pin o of the arm O is adapted to operate, an adjustable block being mounted in said slot whereby 55 the play of the pin in the slot may be regulated to vary the movement imparted to the pusher while the link itself makes a uniform movement. The adjustable block referred to is best seen in Figs. 6 and 15 to 60 18, inclusive, from which figures it will be seen that the block p' is mounted to slide in the opening p and is confined therein by side plates p² united by a transverse bolt p³ and having journaled between their project-

ing edges a cam lock p⁴ adapted to be turned 65 in one direction or the other for releasing or clamping the block in its adjusted position. Graduations p⁵ on the link serve as a ready means for accurately determining the position of the block, thus permitting all of the 70 pushers to be adjusted for handling fuel of any given grade.

From Figs 2, 5 and 6 it will be seen that the pins connecting the links L and P with their respective arms L' and O both project 75 in the same plane transversely of the furnace shaft; or, in other words, the pins are reversely arranged with relation to each other, whereby the links L and P are in the same vertical plane. The links P extend 80 diagonally up to the power shaft Q, through openings or housings in the end walls of the hoppers, as will be readily understood from Figs. 1 and 2, where the openings or housings are indicated at P¹. 85

This arrangement brings all of the operating connections within a narrow vertical area and obviates any interference with them by the tools or implements which are inserted through the openings before referred to 90 or to be presently described.

To provide for the insertion and manipulation of the rousing-bar referred to in the preamble, in such wise that the fuel may be lifted sufficiently to permit of the entry of 95 the proper air supply without breaking up the fire-bed to an injurious degree, rouser-bar openings are provided which are in the plane of operation of the pusher. In other words, the openings are in a plane immediately adjacent to and above the fuel supporting surface of the grate, the principal openings being preferably provided in the pushers themselves, although as will presently appear, other openings are provided in 100 the form of peek openings at each side of the furnace through which the rouser bars may be introduced. 105

By reference to Fig. 3 it will be seen that the pusher G is provided in its front or operative face with a central opening adapted to be normally closed by a gate G' pivotally mounted in the pusher at g and adapted to be swung from the position shown in full lines to that shown in dotted lines, when it is desired to introduce a rousing-bar. Normally the gate is held in its closed position by a locking bolt g² pivotally connected with an operating handle g³, all located in the interior of the pusher and operating within the pusher chamber. Access to these parts is obtained through an outer opening normally closed by a swinging door G², in the outer wall H of the pusher chamber, the proportions of the parts being such that a 115 rousing-bar introduced through the openings 120 may be moved from side to side over practically the whole of the grate area; for ex-

ample, to include the angles of the straight dotted lines g^4 . The handle g^3 may be moved to release the locking bolt by an operating tool G^3 , Fig. 4, and the same tool 5 may be employed for opening the gate G' , thus avoiding any necessity of the attendant reaching into the pusher chamber or being injured by the heated walls.

As will be seen from Fig. 1, the door G^2 10 normally occupies a position at such an angle with respect to its hinges that it will remain in either closed or open position by gravity, thus avoiding the necessity of employing fastening means of any character.

15 In addition to the openings through the pushers, peek openings are formed in the front walls of the furnace at the outer ends of the hoppers in a plane which is coincident with the plane of movement of the pushers, 20 or in other words, immediately above the plane of the fuel supporting surface of the grate. These openings are best seen in Figs. 1 and 2, where they are indicated by the reference character G^4 , the doors or slides 25 for closing the openings being indicated by G^5 .

Below the mechanism hereinbefore described, the front wall of the furnace is provided with the usual ash pit doors S . The 30 handles for operating the rear or dumping sections of the grate extend through the said front wall preferably at each side, as indicated at T , but it will be understood that these portions of the furnace may be of any 35 usual or ordinary construction as they form no part of the present invention, and the same is true of the mechanism for handling the ashes from the ash pit and for conducting and utilizing the combustible gases or 40 products of combustion passing through the wall C into the secondary combustion chamber, and thence to or through the boiler flues.

Reference has heretofore been made to the fact that the preheated air admitted at the 45 point where the fresh fuel is entering the distillation area should be regulated for the purpose of preventing the formation of objectionable smoke, and in the present construction, while the major regulation may be effected through the manipulation of the air forcing means, supplying air to the pre-heating chamber, the specific regulation of the openings at the point referred to is effected by a valve located above each pusher 50 and indicated in Fig. 1 at V . Said valve is movable vertically through the medium of rods V' pivotally connected at their upper end to arms V^2 on rock shafts V^3 journaled at the front of the furnace and having forwardly projecting arms V^4 to the outer ends of which there are pivotally connected downwardly extending operating rods V^5 passing through bearings V^6 on the front edges of the hoppers and by which they may be 55 clamped in adjusted position.

In operation, the fuel supplied through the hoppers passes down onto the dead plates and is advanced by the pushers down over the fuel supporting surface of the grate. The progress of the fuel over the grate is 70 regulated by the range of movement imparted to the pushers, the design being to effectually consume all of the combustible elements before any of the material is allowed to escape or is dumped into the ash 75 pit. The fuel is maintained in a substantially unbroken sheet or bed except in so far as it may be slightly broken up when necessary by the introduction of the rousing-bar, which bar, however, operates solely in the 80 lower stratum of the fuel, or in the ash stratum immediately adjacent the grate surface. The openings for the introduction of the rousing bar are of small size, thus avoiding the entry of any great volume of cold 85 air and it will be particularly noted that any such air as may be permitted to enter must be drawn through the mass of fuel which completely covers and envelops the rousing bar. For the introduction of the rousing 90 bar it is unnecessary to close off the hoppers, the latter function being performed by the curved gates at the bottom of the hoppers 95 only when it is desired to introduce large implements (a hoe for example) for the purpose of leveling off the bed of fuel and more especially for the purpose of pushing the entire body of fuel off of the grate in an emergency requiring this action.

Having thus described my invention, what 100 I claim as new and desire to secure by Letters Patent of the United States, is:

1. In a furnace, a reciprocating pusher associated therewith, means for actuating said pusher consisting of a drive shaft, an eccentric thereon, a link carried by said eccentric, a furnace shaft connected to the link, means for instantly arresting the reciprocation of the pusher located between the furnace shaft and the drive shaft, comprising a 110 block mounted in a slot in said link, side plates rigidly attached to said block, and a cam lock located between the side plates adapted to lock the block against said link.

2. In a fuel feeding device, a pusher, 115 means for actuating same, consisting of a power shaft, a furnace shaft, an arm on said furnace shaft, a link driven from the power shaft provided with a slot connection with said arm, a block slidably mounted in the 120 slot portion of the link, a cam lock for instantly releasing said block in varying positions with respect to the slot, whereby a single movement of the cam lock discontinues the feeding operation.

3. In a fuel feeding device for fuel, a pusher, means for reciprocating same including a rotating power shaft, an oscillatory shaft, connections intermediate said oscillatory shaft and pusher, an arm jour- 125

naled on said power shaft, a link intermediate said arm and power shaft, and a slideable connection intermediate said arm and power shaft consisting of a block seated in a slot in the drive connection, side plates for said block, a cam lock mounted between said side plates, whereby the drive connec-

tion may be instantly broken to arrest the feeding of fuel without interrupting the movement of the power shaft.
